UNITED STATES PATENT OFFICE.

BENJAMIN F. HULL, OF CLINTON, ILLINOIS, ASSIGNOR TO EMMA HULL,
OF SAME PLACE.

INTEREST-CALCULATOR.

SPECIFICATION forming part of Letters Patent No. 444,396, dated January 6, 1891.

Application filed July 24, 1890. Serial No. 359,791. (No model.)

To all whom it may concern:

Be it known that I, BENJAMIN F. HULL, a citizen of the United States of America, residing at Clinton, in the county of De Witt and State of Illinois, have invented certain new and useful Improvements in Interest-Calculators; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

15 This invention relates to improvements in devices for calculating interest.

The object of the invention is to provide a simple, cheap, and compact device consisting of a frame which is adapted to receive a series of printed tablets, said frame having in its inner sides grooves adapted to receive a sliding scale, which can be moved over the tables to indicate, in connection with said tables, the amount of interest for a given time upon a given principal; and it consists in the construction and combination of the parts, as will be hereinafter fully set forth, and particularly pointed out in the claims.

In the accompanying drawings, forming 30 part of this specification, Figure 1 is a plan view of a calculator constructed in accordance with my invention. Fig. 2 is a transverse sectional view showing the device closed. Fig. 3 is a front view. Fig. 4 is a side view of 35 one end of the device, showing the fastening, and Fig. 5 is a detail perspective view of a part of the sliding indicator.

The frame consists of a back board A, to which are rigidly attached side pieces B B and an end piece C. The side pieces B B and end piece C are rigidly attached to the board A, and project a slight distance above the same to provide an open-ended compartment, within which can be placed a series of tables. 40 The inner sides of the pieces B B are provided with longitudinal grooves a, located about centrally in said side pieces, so that the space beneath the groove and above the inner face of the board A can be occupied by 45 a series of interest-tables D, which are divided into vertical columns having figures

which indicate the amount of interest on designated principles placed at the top and bottom of said columns. Each table has a head-line stating the rate of interest, as well as a projecting portion or tab d, upon which the rate of interest is indicated in large figures, as shown.

E refers to a sliding indicator, which moves within the grooves a a and over the tables D, and the right-hand edge of this indicator has printed in a vertical column figures indicative of time, the upper part of the column referring to days, the intermediate portion to months, and the lower end to years. The figures upon said indicator register horizontally with the longitudinal rows of figures upon the tables. This indicator can be moved freely over the tables, and the numbers thereon, when opposite the figures in the vertical columns of the tables, will give the interest on the principal, which is noted at the top and bottom of the column.

To the strip C is secured a cover F, of card board or other suitable material, to which may be attached by paper fastenings a pad or tablet G, which is of such width, length, and thickness that when the cover is closed it will lie within the space above the tables D and between the sides B B, so that the sides 75 of the cover will lie over the upper edges of the side pieces, as shown in the transverse sectional view. The tablet or pad G is made up of a number of sheets of paper in the usual manner, and upon which calculations 80 can be made.

The back A may be provided with a suitable elastic band, which engages with a fixture on the free end of the cover, so as to hold the cover closed when the device is not in use.

90 Each of the interest-tables is made up of separate leaves, and the one it is desired to use is withdrawn and placed on top or immediately beneath the indicator. The indicator, which contains the days, months, and years, by being movable avoids the confusion of having to follow two columns at the same time, and thus lessens the liability to err in arriving at a correct result, and the arrangement is so simple that the question of calculating interest is reduced to mere addition.

In practice, supposing that it should be de-

sired to find the interest on forty dollars for three months and twenty-three days at eight per cent., it is only necessary to insert beneath the indicator the leaf having the interest at eight per cent. The indicator is then moved to the column of figures headed \$40. Follow the indicator down to twenty-three days and the interest will be found to be twenty cents. Moving down to three months the interest will be found to be eighty cents, and twenty cents plus eighty cents equals one dollar, the amount required. By little practice the smaller amounts can be carried mentally and the interest determined accurately 15 and with dispatch.

I am aware that prior to my invention calculating devices having a sliding and graduated scale, as shown in patent to G. M. Knight, dated May 8, 1883, or patent to Curtis, March 20 18, 1884, have heretofore been used, and I do not claim what is shown therein; but

What I do claim as new, and desire to secure by Letters Patent, is—

1. The combination, in a device for calculating interest, of a frame having a base with side pieces B and end piece C rigidly secured thereto, the side pieces being grooved on their inner sides for the reception of a sliding indicator, a series of removable tables confined 25 beneath the grooves in the side pieces by the

indicator, a cover hinged to the end strip C and provided with a tablet, said tablet being adapted to lie within the end and side pieces when the cover is closed, and a retaining device, substantially as set forth. 35

2. The combination, in a device for calculating interest, of a frame having the inner sides of the upper and lower edges grooved for the reception of a sliding indicator, removable interest-tables, a cover hinged thereto and adapted to lie over the upper edges of the side pieces, a space being provided within the frame above the interest-tables and sliding indicator, substantially as shown, and for the purpose set forth. 40

3. In combination with a frame and tables, as shown, said frame having formed in its inner sides grooves or recesses a a, a sliding indicator having laterally-extended ends with rounded corners, and a central connecting portion having a straight edge, the opposite edge being upturned to provide a stiffening and grasping portion, substantially as set forth. 45

In testimony whereof I affix my signature in presence of two witnesses.
